UNITED STATES PATENT OFFICE.

JOHN GODFREY BLAU, OF PHILADELPHIA, PENNSYLVANIA.

SAFETY-GUIDE FOR RAILWAY-CARS.

SPECIFICATION forming part of Letters Patent No. 403,907, dated May 28, 1889.

Application filed December 20, 1887. Serial No. 258,535. (No model.)

To all whom it may concern:

Be it known that I, JOHN GODFREY BLAU, a citizen of the United States, residing at Philadelphia, in the county of Philadelphia and State of Pennsylvania, have invented a new and useful Machine called a "Railroad Safety-Guide," of which the following is a specification.

My invention relates to a machine for the purpose of preventing railroad passenger-cars from leaving the track or derailing, and the several parts of my invention, in combination, are dependent upon each other and mutually contribute to produce a single result; and the objects of my invention are, first, to cover the rail with the flanges of a self-acting guide-block, which rests suspended upon a cross-block with a handle connected thereto; second, to secure the exact elevation and proper adjustment of said handle to a square-sided tube or socket forming part and being connected with the handle of the guide-holder; third, to hook said guide-holder to the so-called "equalizing-bar and bottom brace" of the car-truck; fourth, to secure a strong fastening of said guide-holder by means of a fish-tail reverse-plate and lock-plate jointly, the latter being provided with a bevel, upon which, in connection, a screw with a flat-faced rim will cause a forward pressure and strong fastening. I attain these objects by the mechanism illustrated in the accompanying drawings, in which—

Figure 1, the guide-holder, represents a side view toward its rear, showing its tube or socket with guide-handle and guide-block attached thereto in vertical line. Fig. 2, the guide-block, is a view in perspective, showing its sides and its bevel in blunted extended form. Fig. 3, the guide-handle, with its cross-block, is a vertical view. Fig. 4, the fish-tail reverse-plate, is a rear view, when placed in position, showing its reverse or inner side. Fig. 5, the lock-plate, is a top view showing its bevel. Fig. 6, the screw-head, is a view indicating its position in connection therewith. Fig. 7 shows the device applied to a car-truck. Figs. 4 and 5 placed on top of the handle of the guide-holder in Fig. 1 will show the entire machine in vertical line.

Similar letters refer to similar parts.

The guide-block B, with its two flanges in

parallel line and crescent form, at their base a b cover the rail, and to act as a guide, a, the outside flange is provided with a blunted extended bevel, G, (see Fig. 2.) It is intended that its extended bevel shall slide over the rail of a siding, particularly where such siding rail and main rail form a sharp angle, and be of sufficient depth in vertical line to be even or correspond to the base-line b of the inside flange of crescent of the guide-block, thereby securing a much-desired resistance of the guide-block on the outer rail. The use of said extended bevel, both ends of which are sufficiently elevated to pass over obstructions, will cause the guide-block a lifting or free motion over all sidings, while b, the inside flange of the guide-block, being smooth, takes the inside of rail, but both are sufficiently wide apart to allow the free passage of the rail.

The guide-handle f, Fig. 3, with its cross-block R, its two acute angles, C C, being blunted and of such form and shape as to exactly fill the upper cavity of the guide-block, is passed through the cavity of said guide-block from below, which said guide-block will have a rest upon it, and in turn, by its two sides or braces g g, Fig. 2, which extend upwardly in a diagonal line until they touch the sides of the guide-handle f, act as a balance and permit a sliding or up-and-down motion, by means of which the guide-block becomes self-acting and rests suspended over the rail, as shown in Figs. 1 and 7.

The guide-holder, Fig. 1, is one casting, showing its outer part in vertical parallel form N N. Said parallel form is united in its center in horizontal line by m, the upper parts of said parallel form to right angles P P to a short extent, then terminate in obtuse angles in form of hooks q q, the object thereof being for said guide-holder to rest and fasten on top of the equalizing-bar of the car-truck. To that part m in its center on reverse or inner side at right angles is connected a bar or handle, S, extending in a horizontal line, which handle has on its under or reverse side, near its starting-point, in form of obtuse angle, a lug, t, provided, the object thereof being to permit said handle to rest on top of the so-called "bottom brace" of the car-truck, on which said lug is pressing and resting. The aforesaid handle

S has at its terminal end on its under side a square-sided tube or socket, E, provided, vertical but in line with handle, and its narrow sides are a little shorter and a trifle more 5 apart, so as to leave the tube or socket half-open at its sides, to receive and to adjust the guide-handle *f*, in Fig. 3, after which both are secured and fastened by a pin or rivet of softer metal.

10 As regards the fastening of the guide-holder, I refer to the fish-tail reverse-plate A, Fig. 4, which is a casting or bar-plate, in form to exactly fill the vacant space existing between the equalizing-bar and the so-called "bottom brace," and has a notch, *x*, in the center of its base-line to permit the passage of handle S of guide-holder in Fig. 1. Said fish-tail reverse-plate is provided at both ends at right angles with two short and square pieces, *y y*, of 15 similar thickness, in fish-tail form, of sufficient extent that its points either above or below will press against the so-called "equalizing-bar and bottom brace" from within; but the principal fastening is done by what 20 is called the lock-plate W, Fig. 5. Said lock-plate is intended to secure a strong fastening of the fish-tail reverse-plate and guide-holder jointly to both the equalizing-bar and bottom brace. Said lock-plate is placed on top of 25 the handle S of the guide-holder and immediately in the rear and center of the fish-tail reverse-plate, against which it is pressed, and is provided at its widest end near or at its corners with two extending prongs, *v v*, which, being square and in line of said plate, 30 pass through square holes *h h* in the fish-tail reverse-plate correspondingly opposite. The said lock-plate at its other or narrow end has a bevel, *z*, and is to correspond in width to 35 the handle of the guide-holder, each of which is provided with a screw-hole correspondingly opposite in diagonal line, through which a screw is passed, the hole in the bevel being smooth and notched at its end. As regards 40 the screw, its square screw-head O, Fig. 6, is

45

provided with a flat-faced and round extending rim, *e*, which in pressing against the bevel gives a forward pressure and strong fastening.

To make an additional fastening after the above forward pressure is given, a round hole, *o*, is made through the center of lock-plate W and handle S of guide-holder, Fig. 1, in vertical line, through which a pin is passed.

I am aware that prior to my invention pins, rivets, and screws have been in use. I therefore do not claim them, broadly.

What I do claim as my invention, and desire to secure by Letters Patent, is—

1. The guide-block B, provided with the two diagonal braces *g g* and with the two flanges *a b*, the flange *a* being also provided with the lateral extension G, all substantially as set forth.

2. The guide-handle *f*, with its cross-block R, its two acute angles being blunted at *c c*, upon which the guide-block will rest, substantially as described.

3. The guide-holder N N, consisting of the plate *m*, having hooks *q q*, in combination with the horizontal handle or bar S, having the square socket E, and provided with the fastening-rivet and the lug *t*, all substantially as described.

4. The fish-tail reverse-plate A, having square-sided notch *x* in the center of its base-line, two short and square sides at right angles extending in fish-tail form, *y y*, and two square holes, *h h*, correspondingly opposite the prongs of the lock-plate, all substantially as set forth.

5. The lock-plate W, with its two extending prongs, *v v*, its notched bevel *z*, in combination with the screw having the flat-faced round rim *e*, and the supplementary pin, all substantially as described.

JOHN GODFREY BLAU.
